UNITED STATES PATENT OFFICE.

HARMON P. ELLIOTT, OF WATERTOWN, MASSACHUSETTS.

STENCIL PRINTING SYSTEM AND APPARATUS.

Application filed January 25, 1927. Serial No. 163,525.

This invention relates to stencil printing systems and apparatus and this application is a continuation in part of my co-pending application Serial No. 160,872, filed January 5, 1927.

In the addressing of envelopes and the like by machines employing a collection of stencils bearing the addresses, the stencils when not in actual use are kept usually in classified order in filing drawers of uniform dimensions. When the stencils are to be used for printing they are removed from the drawers and placed in the hoppers or holders of stencil printing machines in the same order in which they are maintained in the drawers. The stencils are moved in successive order from the hopper and are fed through the stencil printing machine and are then delivered in the same order into a second hopper or receiver from which they are adapted to be removed and replaced in the drawers.

This invention relates to and has for its object the provision of a loading or transfer tray having provision for transferring to it the entire contents of a drawer and for transferring to the hopper of the stencil printing machine at one operation the entire contents of the tray thereby facilitating the loading of the machine. The tray is further characterized by being adapted to receive the contents of the receiver of the used stencils and to transfer the used stencils into the empty drawer in the same order in which they were originally disposed.

A further object is a stencil hopper or holder for a stencil printing machine especially adapted to cooperate with the transfer tray.

40 A further object of this invention is generally to improve upon stencil printing apparatus and systems.

Fig. 1 is a perspective view of a transfer tray embodying the invention.

45 Fig. 2 is a sectional detail showing the disposition of the tray in position to receive the entire collection of stencils in a stencil filing drawer.

50 Fig. 3 is a view similar to Fig. 2 but illustrating the final position of the stencils within the transfer tray and with the drawer inverted in condition to be withdrawn.

Fig. 4 is a sectional view along line 4-4 of Fig. 2.

55 Fig. 5 illustrates the manner in which the collection of stencils in the tray is trans-

ferred as a unit to the stencil holder of a stencil printing machine.

The stencils *a* are normally kept in classified order in a single row in drawers having the bottom wall 10, end walls 12, one of which is here shown, and side walls 14, as shown in Figs. 2 and 3. The drawers are open at the top.

The stencil transfer tray embodying this invention comprises a generally channel-shaped member open at its opposite ends and top and having a bottom wall 16 and the two integral upstanding spaced side walls 18. Said side walls are each reflexed outwardly to provide the opposed parallel shelves 20 which are in the same plane and are spaced suitably above the bottom wall 16. The side walls are again reflexed upwardly at the sides of the shelves to provide upstanding sections 22 of suitable height and are then reflexed outwardly to provide a second set of parallel opposed shelves 24. The side walls are again reflexed upwardly at the outer sides of said second shelves to provide 80 the approximately parallel sections 26. The width of the loading tray below the lowermost shelves 18 is adapted to be less than the length of a stencil and the space below said shelves is adapted to receive a stripper 85 plate of a stencil hopper or holder of the stencil printing machine.

When the collection of stencils is in the tray, the stencils are adapted to rest on edge on the lowermost shelves 20 as shown in Fig. 3, the opposed vertical sections 22 of the side walls holding the stencils in alignment. The tray is provided with upstanding resilient fingers 28 at the ends thereof which are located at the ends of and in line with the shelves 20 and are adapted to prevent the collection of stencils from endwise movement out of the tray. The distance between the sets of fingers is adapted to be approximately the length of the stencil space 100 within a stencil filing drawer.

In transferring the contents of a drawer to the stencil tray the drawer is withdrawn from its cabinet and the tray is inverted on top of the drawer with the spring fingers 105 28 disposed between the stencils and the ends of the drawer and with the upper shelves 24 resting upon the top side edges of the drawer as illustrated in Figs. 3 and 4. The drawer and the tray are then inverted and the stencils thus fall into the tray and the drawer can be withdrawn thereby 110

transferring at one operation the entire collection of stencils in the drawer, as a unit, into the tray.

The stencil holder of a stencil printing machine adapted for cooperation with the transfer tray is illustrated in Fig. 5 and has a pair of vertical side walls 30, one being here shown, and a rear wall 32. The holder also has a front wall 36 which comprises a stripper plate. Said plate is attached to the holder only at the bottom and is free from connection with and is spaced from the side walls of the holder.

In transferring the stencils from the tray to the holder, the transfer tray with the collection of stencils therein is held above the stencil holder with the stencils aligned with the stencil space in the holder and with the stripper plate 36 in position to enter the space below the stencils and above the rear wall 16. The transfer tray is then moved downwardly into the position illustrated in Fig. 5 with the stencils entirely within the holder and with the stripper plate disposed behind all of the stencils in the collection. The tray is then moved laterally into a position illustrated in the dotted line, Fig. 5. The edges of the stencils are brought against the stripper plate which holds them from further movement but permits the transfer tray to be stripped clear of the stencils which thereupon are free from the tray in the holder. The stencil receiver of the stencil printing machine is similar in construction to the holder thus described and the collection of stencils in the receiver can be withdrawn by reversing the operation above described.

The stencil holder herein described is claimed in my above-named copending application.

I claim:

1. A transfer tray for a collection of stencils open at the ends and having a bottom wall and upstanding opposed side walls formed with a pair of opposed parallel stencil-supporting shelves spaced above said bottom wall, said side walls also having a second pair of opposed parallel shelves disposed above said stencil supporting shelves and below the tops of said walls, and stencil-retaining members upstanding above and in line with said stencil-supporting shelves at the ends thereof.

2. A transfer tray for a collection of stencils open at the ends and having a bot-

tom wall and upstanding opposed side walls formed with a pair of opposed parallel stencil supporting shelves spaced above said bottom wall, said side walls also having a second pair of opposed parallel shelves disposed above said stencil-supporting shelves and below the tops of said walls, and sets of resilient stencil retaining fingers carried by said side walls at the ends thereof in line with and upstanding above said stencil-supporting shelves and also upstanding above the tops of said side walls.

3. The combination of the stencil holder of a stencil printing machine adapted to contain a pile of superimposed stencils therein, and a tray adapted to contain a column of edgewise-supported stencils and to deliver them into said holder, said holder characterized by having vertical side and rear walls and a vertical front wall which is spaced from said side and rear walls, said tray characterized by comprising an open-ended channel shaped member having a bottom wall, and opposed spaced upstanding side walls, said side walls having opposed parallel stencil-supporting shelves which are spaced above said bottom wall, the space below said stencil-supporting shelves and the bottom of said member being open at least at one end and adapted to receive said front plate of said stencil holder with the stencils contained in said tray being located within said holder, whereby said tray can be withdrawn laterally from said holder to deposit therein its collection of stencils, said front plate engaging bottom edges of the stencils of the collection and retaining them motionless in the holder during such withdrawing movement.

4. A transfer tray for a collection of stencils having spaced parallel side walls provided with spaced parallel stencil-supporting shelves adapted to support a collection of edgewise-disposed stencils thereon, the space between and below said shelves being open for access to the bottom edges of said stencils, and stencil-retaining means located at the ends of and upstanding above said shelves and also above said side walls and constituting end-supports for the stencils when they are clear of the interior of the tray.

In testimony whereof, I have signed my name to this specification.

HARMON P. ELLIOTT.
